ELECTRIC DISCHARGE DEVICE INCLUDING IMPROVED ANODE STRUCTURE

Harvey N. Price, Scotia, N. Y., assignor to General Electric Company, a corporation of New York

Application October 22, 1956, Serial No. 617,362

10 Claims. (Cl. 313—217)

The present invention relates to electric discharge devices, and more particularly to improved gas-filled electric discharge devices including new and improved means adapting same for increased power level operation.

Currently, gas-filled electric discharge devices such, for example, as hydrogen thyratrons are being adapted for operation at substantially high power levels. At these high power levels substantial heat is generated in the devices which makes desirable the employment of high-refractory ceramic envelopes and externally extending electrode elements thereby, respectively, to withstand and efficiently dissipate the increased heat. Additionally, in the type of device to which the present invention is particularly applicable the anode assembly generally includes a metal cup-like sealing member comprising part of the envelope of the device and having a bottom portion which is re-entrant in the envelope and serves as the active anode surface. For desired satisfactory operation this bottom portion or active surface of the sealing member must be maintained planar and parallel to other electrodes in the device; and the sealing member must not be distorted so as to crack the metal-to-ceramic seals between the anode assembly and ceramic portions of the envelope. Maintaining the active surface in the mentioned planar and parallel relations and avoiding seal-damaging distortions have been problems owing to a tendency of the sealing member to be distorted as a result of atmospheric pressure at operating temperatures and during cooling following brazing of the structure to the associated ceramic portions of the envelope. These problems have been aggravated by the fact that, from the standpoint of providing suitable brazes between the cup-like sealing member and the ceramic portions of the envelope, it is desirable that the sealing member be formed of relatively thin material and preferably copper, which construction affords little resistance to distortion stresses. Heretofore, it was attempted to cope with this problem by bonding a relatively massive stiffening plate to the outer surface of the bottom or active portion of the sealing member. This solution has not proved completely satisfactory, especially in high power level devices characterized by high heat generation, first, because of tendencies toward distortion resulting from the differentials in expansion and contraction rates between the copper and steel and, secondly, because the relatively massive steel plate tended both to retain heat and to shield a substantial portion of the relatively more heat-conductive copper sealing member from the normally cooling air currents, thereby resulting in decreased cooling efficiency. Furthermore, in high power level operation the electron and ion bombardment of the internal elements and surfaces of the device is so substantial that it has been found necessary to secure to the inner surface of the mentioned cup-like sealing member a high-refractory metal element adapted for serving as the active anode surface. This element has also been found to cause distortion of the anode assembly during cooling after brazing because of a differential in thermal expansion

2

and contraction rates between the materials of the element, the copper sealing member and the externally disposed steel stiffening plate. In order to alleviate this condition it has been proposed to secure the sealing member and the high-refractory elements at only limited corresponding central portions. This type of structure, however, is not considered satisfactory in that it would have the adverse effects of reducing substantially the heat transfer from the active anode surface to the external portion of the sealing member and thus tend to render the device less adapted for high power level operation.

Accordingly, the primary object of the present invention is to provide a new and improved electric discharge device adapted for increased high power level operation.

Another object of the present invention is to provide a new and improved gas-filled electric discharge device including new and improved means for increasing heat dissipation therefrom.

Another object of the present invention is to provide a new and improved gas filled electric discharge device including new and improved means for maintaining desired electrode spacing therein and insuring against sealing failures.

Further objects and advantages of the present invention will become apparent as the following description proceeds and the features of novelty which characterize the invention will be pointed out with particularity in the claims annexed to and forming part of this specification.

In carrying out the objects of the invention there is provided a device comprising a gas-filled envelope. The envelope comprises ceramic insulative sections and mutually insulated electrode assemblies which support electrode elements in desired spaced relation in the device and form part of the envelope wall. The electrode assemblies comprise high heat conductivity metal sealing members which are thin relative to the insulators and include substantial portions extending externally of the envelope. One of the electrode assemblies is an anode assembly comprising a cup-like sealing member re-entrant in the associated ceramic insulator. Bonded to that surface of this member which is disposed internally of the envelope is a high-refractory metal element comprising a planar active anode surface. Bonded to the opposite surface of the sealing member is a member which occupies an inappreciable volume in the bottom of the sealing member, is formed of low heat retentivity material and is of substantially similar thermal expansion and contraction characteristics as the high refractory metal element. Carried by the member disposed in the bottom of the sealing member is a heat radiating element.

For a better understanding of the invention reference may be had to the accompanying drawing wherein is illustrated an electric discharge device constructed in accordance with a preferred embodiment of the present invention.

The electric discharge device there illustrated is a hydrogen thyratron comprising an envelope 1, a cathode-reservoir assembly 2, a grid assembly 3 and an anode assembly 4.

The envelope 1 comprises three generally cylindrically ceramic sections 5, 6 and 7. The sections 5-7 may be formed of any suitable high-strength and high-refractory ceramic material adapted for being metalized in order to facilitate the provision of ceramic-to-metal bonds or brazes between the insulative sections and portions of the mentioned assemblies. For example, the sections 5-7 may each be formed of ceramic materials generally known in the art as "alumina," which materials are adapted for being provided with metalized areas in the manner disclosed in U. S. Patent No. 2,667,427 issued

January 26, 1954 to Henry J. Nolte and assigned to the same assignee as the present invention.

The cathode-reservoir assembly 2 includes a header closing the lower end of the envelope 1 and generally designated 8. The header 8 supports in a suitably mutually insulative manner a plurality of leads 9 which extend through the header in a sealed manner and internally of the envelope support and make suitable electrical connections to the cathode structure and a hydrogen reservoir (not shown). Secured to the leads 9 are flexible conductors 10, each carrying a lug 11. The header 8 further includes a sealing ring 12 which is bonded to a suitably previously metalized lower edge of the insulative section 5, as by means of a silver-copper brazing material. By way of example, and with a ceramic which had been metalized by the above-mentioned titanium hydride process, the brazing material may comprise approximately 72% silver and approximately 28% copper and the braze may be effected in a hydrogen furnace in a temperature range approximately between 778° and 850°. Also, suitably bonded to the exterior of the ring 12 is an annular metallic flange 13 adapted for facilitating mounting of the device.

Internally of the envelope, the sealing ring 12 may be suitably electrically connected to the above-mentioned cathode structure which is shown in outline and generally designated 14. Thus, the ring 12 and associated flange 13 are adapted for conjointly serving as the electrical contact for the cathode.

As illustrated in the drawing the cathode structure 14 can include a shielding structure including a cylinder 15 suitably mounted about the upper end of the cathode structure 14, a plurality of wire-like supports 16 extending radially inwardly from the upper edge of the cylinder 15 and an imperforate metallic disk-like member or shield 17 secured centrally on the supports 16. In this arrangement the diameter of the member 17 is less than that of the cylinder and thereby is effective for enabling passage therewith of electrons originating at the cathode while at the same time effecting the desired shielding.

Sealed between the opposed edges of the ceramic insulators 5 and 6, as by substantially the same brazing process described above in respect to the sealing ring 12, is a sealing ring 18. The sealing ring 18 comprises a rim-like portion of an inverted cup-like grid support structure 19. Formed in the side wall of the member 19 adjacent the ring 18 is a plurality of circumferentially spaced outwardly extending protrusions 20. The protrusions 20 are engageable with the inner wall of the ceramic section 6 for insuring maintenance of a desired spaced relation between the upper portion of the member 19 and the section 6 during operation of the device. The grid proper comprises a perforated bottom portion 21 of the structure 19 and a perforated plate 22 secured in spaced parallel relation to the bottom portion 21 as by a plurality of circumferentially arranged brackets 23. The perforations in the plate 22 and the perforations in the portion 21 of the member 19 are in offset relation so as to avoid straight direct passage of electrons and ions therethrough. Disposed centrally between the portion 21 and the plate 22, for the purpose of maintaining a desired spaced relation therebetween, is a spacer element 24.

The sealing ring 18 serve both as an electrical contact for the grid and extends substantially outwardly for increased heat dissipation.

The anode assembly 4 comprises a cup-like sealing member 25 including a rim portion 26 and a planar bottom portion 27. The member 25 is preferably formed of copper and is relatively thin compared to the insulative sections. The rim portion 26 is bonded between previously metalized opposed edge portions of the ceramic insulative sections 6 and 7 in the same manner as the grid sealing ring 18, between the sections 5 and 6. As seen in the drawing the rim 26 extends substantially

outwardly of the insulative sections of the envelope, and thus contributes to the cooling of the device. The member 25 includes a plurality of protrusions 28 which can be substantially identical in construction and purpose to the protrusions 20 in the member 19.

The sealing member 25 is substantially re-entrant in the upper portion of the insulative section 6 for thus disposing the planar bottom portion 27 thereof in substantially close parallel spaced relation to the planar grid element 21. Bonded to that surface of the bottom portion 27 which is disposed internally of the envelope 1 is a disk-like element or plate 30 formed of a high-refractory metal which is preferably molybdenum. The plate 30 is preferably about .060-.070 of an inch and is bonded to the anode sealing member completely throughout the opposed areas thereof, as indicated at 31, and the bond is preferably effected by means of a gold-copper alloy brazing material with the braze being effected in a hydrogen atmosphere at approximately 1050° centigrade. The inwardly facing surface of the member 30 serves as the active anode surface of the assembly 4 and is substantially planar and equally spaced from the planar surface of the grid member 21 throughout the corresponding portions thereof. The high-refractory nature of the material of the plate 30 adapts the active anode surface to withstand without deterioration greater electron and ion bombardment and, thus, the device is adapted for efficient higher power level operations. Additionally, the gold-copper alloy braze completely across the opposed surfaces of the sealing member bottom 27 and the element 30 provides for maximum heat transfer from the active anode surface to the anode sealing member 25 for heat dissipation thereby, which feature further adapts the device for efficient high power level operation.

Bonded to the external surface of the portion 27 of the sealing member 25 or the surface opposite the element 30, and as at 32, is an element 33. The element 33 is formed of a material and to a thickness and configuration whereby it is adapted for having substantially the same thermal expansion and contraction characteristics as the element 30. Thus, the member 33 is adapted for "backing up" or reinforcing the bottom portion 27 of the sealing members 25 and the high-refractory material plate 30 without adversely affecting the electrode spacing or ceramic-to-metal seals at the rim 26. Additionally, the element 33 is formed of a material having low heat retentivity and which will provide the desired thermal expansion and contraction matching characteristics relative to the element 30 without filling any appreciable volume of the cup-like sealing member 25. As seen in the drawing, the element 33 covers only the bottom of the member 25 and, thus, leaves the sidewall portions of the member 25 exposed to air currents therein for maximum heat dissipation from the device. Preferably the member 33 is formed of the same dimensions and material as the element 30. However, it will be understood that, inasmuch as the member 33 need not be formed of a high-refractory metal, it is not essential that it be formed of molybdenum or the like.

Suitably bonded centrally in the member 33 and in satisfactory electrically conductive relation with the elements comprising the anode assembly is an upstanding stud or connector 34, adapted for serving as the anode contact. Additionally, disposed about the stud 34 and bonded to the member 33 is a hollow cylindrical metal element 35 adapted for serving as a heat radiator thereby to increase heat dissipation from the anode assembly 4.

Thus, it will be seen that I have provided a new and improved gas-filled electric discharge device including new and improved means for increasing heat dissipation therefrom, maintaining desired electrode spacing and insuring against sealing failures during assembly and subsequent operation, whereby the device is adapted for efficient higher level power operation.

While the specific embodiment of the present invention has been shown and described, it is not desired that the invention be limited to the particular form shown and described, and it is intended by the appended claims to cover all modifications within the spirit and scope of the invention.

What I claim as new and desire to secure by Letters Patent of the United States is:

1. An electric discharge device comprising, an envelope including a cylindrical insulative section, an electrode assembly including a conductive member of thin metal extending across one end of said insulative section, said member being bonded to said one end of said insulative section and extending substantially outwardly therefrom, a metal plate bonded to one surface of said member for serving as an active surface of said assembly, and a member of low heat-retentivity material and having substantially the same thermal expansion and contraction characteristics as said plate bonded to the opposite surface of said conductive member.

2. An electric discharge device as in claim 1, including a heat radiating element bonded to said member of low heat-retentivity material.

3. An electric discharge device comprising, an envelope including a cylindrical insulative section, an electrode assembly including a conductive member of thin metal extending across one end of said insulative section and bonded at the outer edge to said insulative section, a high-refractory material plate bonded to the surface of said conductive member facing into said cylindrical section for serving as an active electrode surface, and a plate of substantially the same thermal expansion and contraction characteristics as said first-mentioned plate bonded to the opposite surface of said conductive member.

4. An electric discharge device comprising, electrode structure including an anode assembly, an enclosing envelope including a cylindrical insulative section, said anode assembly including a conductive cup-like member of thin metal having a bottom portion re-entrant in one end of said insulative section and a rim portion bonded to said insulative section, and identical metal plates bonded to the opposite surfaces of said bottom portion of said member.

5. An electric discharge device as in claim 4, including a hollow cylindrical heat-radiating element disposed in said cup-like member and bonded to the metal plate on the corresponding side of said bottom portion.

6. A gas-filled electric discharge device comprising, electrode structure including an anode assembly, an enclosing envelope including a cylindrical ceramic section, said anode assembly including a cup-like member of conductive material having a planar bottom re-entrant in one end of said ceramic section and a rim portion bonded to said ceramic section, a high-refractory metal plate extending and completely bonded across the surface

of said planar bottom innermost in said ceramic section for serving as the active anode surface of said device, and a thin metal plate of substantially the same thermal expansion and contraction characteristics as said first-mentioned plate extending and completely bonded across the opposite surface of said planar bottom of said conductive member.

7. A gas-filled electric discharge device comprising, electrode structure including an anode assembly, an enclosing envelope including a cylindrical ceramic section, said anode assembly including a cup-like member of thin metal and having a planar bottom re-entrant in one end of said ceramic section and a rim portion bonded to said ceramic section and extending substantially outwardly therefrom, a thin molybdenum plate bonded to the surface of said planar bottom facing into said ceramic section for serving as the active anode surface of said device, and a plate of substantially identical dimensions and material bonded to the surface of said planar bottom opposite said first-mentioned plate.

8. In an electric discharge device a cylindrical insulator, a thin sheet metal member extending across one end of said insulator and bonded thereto, said member being solely supported by said insulator and including a peripheral portion extending radially substantially outwardly from the side walls of said insulator, and a pair of similar metal plates bonded completely thereacross to opposite surfaces of said sheet metal member, one of said plates serving as an active electrode and the other cooperating with said one plate for minimizing distortion of said sheet metal member therebetween.

9. An electric discharge device comprising a cylindrical insulator, a metal member extending across one end of said insulator and bonded thereto, said member being solely supported by said insulator, and a pair of similar metal plates bonded completely thereacross to opposite surfaces of said metal member, one of said plates serving as an active electrode and the other cooperating with said one plate for minimizing distortion of said metal member therebetween.

10. An electric discharge device as in claim 9, including a heat dissipating member bonded to said other metal plate.
